UNITED STATES PATENT OFFICE.

JAMES V. LISY, OF RAVENNA, NEBRASKA.

CLAMP.

1,275,452.

Specification of Letters Patent. Patented Aug. 13, 1918.

Application filed March 29, 1918. Serial No. 225,534.

To all whom it may concern:

Be it known that I, JAMES V. LISY, a citizen of the United States, residing at Ravenna, in the county of Buffalo and State 5 of Nebraska, have invented new and useful Improvements in Clamps, of which the following is a specification.

This invention relates to a clamp which is primarily intended to be employed to 10 connect the trace with the hames strap, although the construction of the clamp is such that it may be advantageously employed to connect other straps comprising a part of a harness if found desirable.

15 The primary object of the invention is to provide a clamp of this character which when used in connection with the buckle now employed to connect the trace and hame strap will not only take the strain off of the buckle, but will prevent the trace being worn at this point while the harness is in use.

20 A further object of the invention is to so construct the clamp that the greater the strain upon the trace the more firmly the trace will be held in engagement with the hames strap by the clamp.

25 A still further object of the invention is to provide a clamp which may be easily applied to a harness without necessitating the service of a saddler for this purpose.

30 With these and other objects in view the invention resides in the novel combination and arrangement of parts which will be 35 hereinafter described and claimed.

In the drawing:

Figure 1 is a view in side elevation of a portion of a harness wherein the trace is connected with the hames tug strap by 40 clamps constructed in accordance with the invention.

Fig. 2 is an enlarged longitudinal sectional view through one of the clamps shown in Fig. 1.

45 Fig. 3 is a top plan view of Fig. 1 wherein the movable jaws of the clamps are shown in position to permit the adjustment of the trace with relation to the hames tug strap.

Fig. 4 is a perspective view of the fixed 50 jaw of the clamp and

Fig. 5 is a similar view of the movable jaw of the clamp.

Like characters of reference denote the corresponding parts throughout the various views in the drawing.

55

Referring now to the drawing in detail the letter A designates a portion of a harness wherein a trace 10 is connected with a hames tug strap 11 by a pair of clamps 12 struck in accordance with the invention 60 and adapted to prevent undue strain being imposed upon a buckle 13 while the harness is in use.

65 Each of the clamps 12 comprises a fixed jaw 14 which is in the form of an eye plate and has its web portion passed between and secured to the strips from which the tug strap 11 is formed. By mounting the fixed jaw of the clamp on the tug strap in the manner described above the flanges at opposite side of the web portion of the fixed jaw through their engagement with the side of the strip from which the tug strap are formed prevent undue strain being imposed upon the rivets 12' employed to connect the 75 fixed jaw with the tug strap.

70 The movable jaw of the clamp comprises a plate 15 which is flanged as shown to provide the movable jaw with a longitudinally extending channel through which the trace 10 is passed. Extending transversely of the outer face of the plate 15 is a shaft 16 which is suitably secured to the plate and has its end passed through openings in links 17. The links 17 are pivotally connected with the flanges at the sides of the fixed jaw of the clamp and not only permit the movable jaw of the clamp to be moved toward or away from the fixed jaw but serves to hold the movable jaw in alignment with the fixed 80 jaw of the clamp when the harness is in use.

85 Fixed to the inner face of the plate 15 is a stud 18 which is received in an opening in a longitudinally extending row of openings in the trace 10 so that, when a pull is exerted upon the trace 10 the movable jaw of the clamp will be moved in the direction of the pull and will force the trace firmly against the hames tug strap 11.

90 With reference to Fig. 2 in the drawing 100 it will be apparent that the greater the strain imposed on the trace 10 the harder the trace will be forced against the tug strap 11 to prevent undue strain being im-

posed on the buckle 13 or the movement of the straps 10 and 11 with relation to each other.

When it is desired to adjust the trace 10 with relation to the hames tug strap the trace is disengaged from the stud on the buckle 13 and the movable jaw of the clamp 12 swung away from the fixed jaw of the clamp so that, by disengaging the trace 10 from the stud on the movable jaw of the clamp the trace may be drawn through the channel in the movable jaw of the clamp to the desired extent.

After the trace 10 has been adjusted and the movable jaw of the clamp swung to clamping position the trace may be engaged with the stud on the buckle 13.

From the foregoing description taken in connection with the accompanying drawing it is apparent that a clamp has been provided for connecting a trace with the hames tug strap which is so constructed that an undue strain will be prevented from being imposed on the buckle employed in connec-

tion with these members and the adjustment of the trace with relation to the hames tug strap may be readily accomplished if the occasion requires.

Having thus described the invention what is claimed as new is:—

In a device for the purpose set forth, the combination with a tug strap comprising two strips and a trace strap, of a clamp for said straps comprising an eye plate and a channeled plate, said eye plate receiving the strips of the tug strap on the webs thereof, means passing through said strips and said web for securing the tug strap to the eye plate, the trace strap received in the channeled plate, a lug in said channeled plate passing through said trace strap, trunnions arranged centrally of the eye plate, a shaft arranged centrally and on the under face of the channeled plate, and links connecting said shaft and trunnions.

In testimony whereof I affix my signature.

JAMES V. LISY.
